CLAIM

The ornamental design for a device for a biological reaction filter for medical analysis, as shown.

DESCRIPTION

FIG. 1 is a top plane view of the biological reaction filter for medical analysis according to my invention.

FIG. 2 is a bottom plane view thereof.

FIGS. 3 and 4 are respectively left side and right side views of the device.

FIG. 5 is a front view thereof.

FIG. 6 is the corresponding rear view.
